US0D1093419S

(12) **United States Design Patent** (10) **Patent No.:** **US D1,093,419 S**
Mozeika (45) **Date of Patent:** **** Sep. 16, 2025**

(54) **DISPLAY SCREEN OR PORTION THEREOF HAVING A GRAPHICAL USER INTERFACE**

(71) Applicant: **Flo Free LLC**, Wall, NJ (US)

(72) Inventor: **David James Mozeika**, Wall, NJ (US)

(73) Assignee: **Flo Free LLC**, Belmar, NJ (US)

(**) Term: **15 Years**

(21) Appl. No.: **29/821,403**

(22) Filed: **Dec. 29, 2021**

(57) **CLAIM**

The ornamental design for a display screen or portion thereof having a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof having a graphical user interface.

The dot-dashed lines depict a display screen or portion thereof and the boundary of the claimed design that form no part of the claimed design. The broken lines depict portions of the graphical user interface and form no part of the claimed design.
